CLAIM

The ornamental design for a skin exfoliating device, as shown and described.

DESCRIPTION

FIG. 1 is a perspective view of a skin exfoliating device showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof, shown in an environment of use; and,

FIG. 10 is an enlarged view of the encircled portion 10 of FIG. 1.

The evenly spaced broken lines illustrate portions of the skin exfoliating device that form no part of the claimed design. In FIG. 9, the broken lines showing a cradle illustrate environmental subject matter and form no part of the claim. The dot-dash broken lines in FIGS. 1 and 10 illustrate enlarged view indicators and form no part of the claimed design.
